(57) CLAIM

I claim the ornamental design for a head for golf putter, as shown and described.

DESCRIPTION

FIG. 1 is a perspective view of the head for golf putter showing my new design;

FIG. 2 is a front view thereof;

FIG. 3 is a back view thereof;

FIG. 4 is a top view thereof;

FIG. 5 is a bottom view thereof; and,

FIG. 6 is a right side view thereof which is the mirror image of the left side.
The broken line showing of portions of the head for golf putter is included for the purpose of illustrating and forms no part of the claimed design.
